FUEL PUMP

Kenneth C. Burkhart, Prosser, Wash.

Application September 18, 1935, Serial No. 41,043

2 Claims. (Cl. 103—41)

This invention relates in general to fuel pumps used in fuel systems of internal combustion engines and relates specifically to a fuel pump of the type having as a part of its structure a pressure-responsive, reciprocatory pumping member and inlet and outlet check valves.

The invention consists in supplying a vent to allow fuel that is trapped in the pumping chamber of a fuel pump to flow toward the fuel supply. 10 This vent operates to relieve the pressure existing in the pumping chamber when the pump is stopped during the portion of its cycle that it is discharging fuel. A somewhat uniform though pulsating pressure is realized from the outlet, in pumps of current construction, by employing resilient means which conditionally advance the pumping member during its discharge stroke, and by interposing an air-dome for a hydraulic cushion. When the pump is stopped during the particular part of its cycle in which the linkage has released the diaphragm, spring pressure discharges the reserve capacity of the pump, and in this manner, the fuel pump often continues supplying fuel under pressure for some time thereafter. 25 If the float valve in the carburetor has the least tendency to leak, a charge of fuel flows past it and into the float chamber. The resulting rise in fuel level causes the carburetor to overflow or the mixture to be too rich when starting if the motor is warm, making starting difficult and causing uneven idling until the normal level is attained.

The fuel pumps now in general use with internal combustion engines do not provide escaping means for the fuel which is confined in the pumping chamber except the outlet check valve which allows the fuel to flow toward the carburetor. If the float valve in the carburetor, which opens or closes in response to the fuel level within the carburetor, closes the inlet fuel passage of the carburetor, the fuel cannot escape even into the carburetor. Furthermore, in the normal operation of the fuel pump, the spring disposed beneath the diaphragm tends to normally force the diaphragm upward and thereby forces the fuel through the outlet check valve; but, if the carburetor has a sufficient supply of fuel and the float valve prevents the entrance of the fuel being pumped by the fuel pump, thus acting as a brake against the normal flow of the fuel being pumped, a pulsating or surging of the fuel is created by the action of the pump diaphragm and by the hydraulic shock arising from the abrupt closing of the inlet check valve. These forces tend to vibrate the float valve to such an extent as to cause

undue wear and frequent replacement of said valve.

It has also been found that, when the engine ceases to operate, and if at said time, the diaphragm happens to be on the discharge stroke, it necessarily tends to return to its normal position of rest due to the action of the spring lying thereunder. When the diaphragm is in this position, the pump chamber is charged with fuel, and the inlet valve is closed. Consequently, some of the fuel is displaced by the movement of the diaphragm to its normal position of rest; and the displaced fuel must of necessity pass through the outlet check valve toward the carburetor. If the carburetor float valve is new and tight fitting, it will successfully resist the entrance of this excess fuel into the carburetor; but as soon as there is the slightest wear on the float valve, this displaced fuel will enter into the carburetor and flood the same, making it difficult to re-start the engine.

It is within the contemplation of my invention to overcome the above inherent disadvantages of the present type of fuel pumps. This is accomplished by providing escaping means between the fuel supply line and the carburetor, but preferably within the fuel pump structure so that the displaced fuel will return to the supply line rather than attempt to pass into the carburetor through the outlet check valve.

The quintessence of the invention is to provide a by-pass or relief port which is capable of preventing the flow of fuel into the carburetor after the internal combustion engine has been stopped with the pumping member on the discharge stroke, and is further capable of dampening and relieving the shock present in the pulsating and surging of the fuel; and, in this manner, the excessive vibration of the float valve of the carburetor is for all practical purposes eliminated.

An important object of the invention is to provide a fuel pump which avoids the flooding of the carburetor after the motor has been stopped.

An equally important object of the invention is to provide means within the fuel pump which prevents the excessive vibration of the float valve in the carburetor.

Not all the advantages and characteristic features have here been stated. Many more will become apparent from the following description and accompanying drawing which illustrates the application of the invention, and in which:

Figure 1 is a side elevation of a fuel pump of the diaphragm type shown connected to a carburetor, a part of the fuel pump structure being broken

away to illustrate the position of the inlet check valve embodying my invention during the intake stroke of the fuel pump.

Figure 2 is a side elevation, partially in section, 5 of the fuel pump shown in Figure 1, graphically illustrating the position of the inlet check valve embodying my invention at the beginning of the discharge stroke of the diaphragm.

Figure 3 is a fragmentary, sectional, side elevation 10 of the inlet check valve embodying my invention showing the details of construction of said valve.

Figure 4 is a fragmentary, sectional, side elevation 15 of a portion of a fuel pump, showing the embodiment of my invention in a modified form as a part of the pump casing rather than a part of the inlet check valve.

Like reference characters are intended to identify similar parts throughout the several views.

20 The fuel pump, generally designated by reference character A, is of the diaphragm type and is normally attached to the crank case 1 in any well known manner. There is an opening 2 in the crank case through which rocker arm 3 of the 25 fuel pump passes. Disposed on the cam shaft 4 is an eccentric cam 5 which engages with the surface 6 of rocker arm 3 to actuate the rocker arm. The fuel pump consists of a body element 7 having therein an irregular interior 8 in which there is 30 secured diaphragm 9. Diaphragm 9 is composed of a specially treated flexible material which is impervious to gasoline and benzol and forms a pump chamber 10 within the interior 8. Disc 11 is disposed on the top surface of the diaphragm 35 9 and disc 12 is disposed adjacent the bottom surface of the diaphragm. These discs are held in tight working relationship to the diaphragm 9 by stem 13 which has a slot, not shown, passing through its lower end 14. Surrounding stem 13 40 is a resilient element, such as spring 15. This spring is guided in its movement by cylindrical member 16 formed integral with body element 7 and is normally maintained in compressed condition between disc 12 and ledge 17 extending 45 from cylindrical member 16 so that an upward thrust upon the diaphragm always exists.

Secured to the body element 7 is shaft 18 about 50 which rocker arm 3 is journaled. End 19 of rocker arm 3 has a yoke, not shown, formed therein through which shaft 18 passes. Link 21 has 55 one of its ends 22 passing through the slot (not shown) formed within stem 13 and the other end 23 is journaled on shaft 18 so that the inclined surface of end 23 of link 21 coincides with the inclined surface which is formed at the base of the yoke. A resilient member 24 is held between anchor surface 25 formed within body element 7 and seat 26 formed within rocker arm 3. This 60 spring is adapted to at all times maintain the surface 6 of rocker arm 3 in contact with the eccentric cam 5.

Inlet port 27 communicates with the interior 65 of pump chamber 10. Port 27 also communicates with the interior of sediment chamber 28. An inlet check valve, designated generally by reference character B and shown enlarged in Figure 3 of the drawing, is disposed within the inlet port 27 between the pump chamber 10 and sediment chamber 28. This valve consists of a disc 29 capable of sitting on seat 30 formed within the 70 inlet port against the normal thrust of a resilient element, such as a spring 31. Disc 29 has a relief port or opening 32 formed therein, the purpose 75 of which will be clarified in the modus operandi to be forthwith set forth. An outlet port 33 also

communicates with the pump chamber 10 and leads to the carburetor 34. An outlet check valve, generally designated by reference character C, is disposed within the port 33 and consists generally of a disc 34 capable of being seated upon seat 35 by the thrust action of a resilient element, such as spring 36.

Modus operandi

It at once becomes obvious that the downward 10 movement of the diaphragm is controlled by the linkage which in turn is controlled by the eccentric cam 5 on the cam shaft. The rotation of the eccentric cam actuates the rocker arm 3 which pushes link 21 downward causing a downward 15 pull to be exerted against stem 13 which pulls the diaphragm 9 downward against the spring 15. Since the diaphragm in its movement almost fills the pump chamber 10, it becomes clear that in its downward movement a negative pressure approaching a vacuum is created in the pump chamber. 20

On the suction stroke of the pump, fuel enters from the sediment chamber 28 through the inlet check valve B into the pump chamber 10. In 25 this position, the cam shaft is rotated to the low side of the eccentric cam 5. On the return stroke of the pump, the spring pressure thrusts the diaphragm upward forcing fuel from the pump chamber 10 through the outlet check valve C into 30 the carburetor. But when the carburetor bowl is filled, the float in the carburetor shuts off the valve, causing the pumped fuel to accumulate and remain in the pump chamber under sufficient pressure to resist the upward movement of the 35 diaphragm 9 against the thrust of the spring 8.

The "braking" and regulating action on the normal pulsating flow of the fuel from the pump to the carburetor vibrates excessively the carburetor valve and causes undue wear thereon. Furthermore, if the carburetor valve is not tight fitting due to wear or other conditions, such a braking action is impaired and the fuel continues to flow into the carburetor and floods the same. Relief port 32, formed in disc 29, allows a part of the 45 fuel which is forced back by the carburetor valve to flow back into the sediment tank 28. By this construction, excessive vibrations caused to the carburetor valve in normal operation are damped 50 and the flooding is prevented by maintaining the valve in good condition, and by providing a vent to relieve pressure in the pumping chamber after the motor is stopped. The port or opening 32, while sufficient in area to allow a portion 55 of the confined fuel to flow back into the sediment tank, does not noticeably impair the efficiency of the operation of the inlet check valve or any other part or action of the pump.

The same result may be obtained by providing a relief passage 37 within the pump casing so that 60 it communicates with inlet port 27 and sediment chamber 28, as graphically illustrated in Figure 4.

The invention has been described in connection with a specific illustrative embodiment disclosing a definite arrangement of parts. However, it will be understood that many variants thereof are possible to those skilled in the art, and the invention, in its broader aspect, is not limited to the specific construction herein described and 65 shown, as changes in size, proportions, configurations, substitutions and combinations of forms, parts, members and features, may be made without departing from the broad spirit of this invention. 70

Having thus disclosed my invention, what I claim as new and upon which I desire to secure Letters Patent is:

- 5 1. In a pump of the class described, in combination with a diaphragm, linkage for operating said diaphragm, an inlet check valve and an outlet check valve, of a valve disc incorporated within the inlet check valve, said valve disc having embodied therein a relief port adapted to receive 10 excessive fuel from the pump chamber and to dampen the excessive pulsations of the carburetor valve and diaphragm.
2. In combination with a pump of that type

which includes a pressure-responsive reciprocating pumping element movable in one direction in a pumping chamber by actuating means serving to impart variable strokes, and conditionally advanced in the opposite direction by resilient 5 means during its discharge strokes, of an inlet check valve comprising a valve disc, said valve disc having a port therein adapted to by-pass a flow of excess fuel displaced from the pumping chamber by action of said resilient means after 10 said actuating means have ceased to function during the discharge stroke.

KENNETH C. BURKHART.
